UNITED STATES PATENT OFFICE.

WILSON SARGENT, OF PICTON, ONTARIO, CANADA, ASSIGNEE OF ONE-HALF TO FREDERICK T. KNIGHT, OF PICTON, CANADA.

CYLINDER GRINDER.

Application filed January 23, 1923. Serial No. 614,883.

To all whom it may concern:

Be it known that I, Wilson Sargent, a subject of the King of Great Britain, and resident of the town of Picton, county of Prince Edward, Province of Ontario, in the Dominion of Canada, have invented certain new and useful Improvements in Cylinder Grinders, described in the following specification and illustrated in the accompanying drawings, that form part of the same.

The principal objects of the invention are to produce a tool for grinding engine cylinders, without removing the engine from its bed or the cylinders from the base, which will be extremely accurate in its work and may be easily and quickly adjusted.

The principal feature of the invention consists in the novel manner of supporting the grinding stones whereby they are yieldingly sustained uniformly from end to end by a pivotal member engaging the inward side of the stone.

In the drawings, Figure 1 is a longitudinal part sectional view on the line 1—1 of Figure 2.

Figure 2 is a cross section of the grinder on the line 2—2 of Figure 1.

Figure 3 is a perspective sectional detail of one end of a grinder stone and holder.

Rotatable tools with radially adjustable stones have been previously proposed but the great difficulty has been to keep them in uniform adjustment from end to end.

In the construction herein shown a circular block 1 is formed with a plurality of longitudinal radial slots 2, four being shown, though any other desirable number may be used.

One end of the block 1 is provided with a threaded plug 3 to which is connected a suitable flexible joint 4 by means of which the grinder is operated. The plug 3 is bored centrally to receive the end 5 of the spindle 6 which is threaded right and left. The reduced end 7 of the spindle 6 is journaled in the bearing 8 at the opposite end of the block 1 and is provided with a screw slot 9 for turning the spindle.

Cone nuts 10 and 11 are threaded on the opposite ends of the spindle 6.

The stone holders 12 having parallel sides are slidably arranged in the radial slots 2 and are formed with beveled ends 13 to engage the cones 10 and 11. Grub screws 14

secure the holders 12 in their adjusted positions.

Each of the holders is formed with a longitudinal recess opening to the outward side and in the bottom of each recess is arranged a slightly transversely curved plate 15 extending from end to end. The plates 15 are pivotally supported at one side by spindles 16 or pivot screws 17 secured in the ends of the holder and the outer curved face engages the stone 17' which is slidably arranged in the recess.

The plates 15 are spring pressed outwardly by coil springs 18 bedded in holes 19 in the bottom of the recesses and engaging the inner sides of the plates at the side opposite to their pivotal support.

The stones are formed with slots 19' at the ends to receive the screws 20 which hold the stone from accidental displacement while allowing plenty of latitude for radial movement.

It will be readily understood that the pressure of the springs 18 is transmitted to the stones through the medium of the pivot plates 15, consequently the pressure will be uniform from end to end and a uniform diameter will be ground by the stones.

The adjustment is very simple, it being merely necessary to loosen the set screws 14 and turn the spindle 6 to adjust the cone units to obtain the desired diameter which can thus be regulated very accurately.

What I claim as my invention is:—

1. In a cylinder grinder, the combination with a rotatable block and a radially adjustable member therein, of a radially adjustable stone, a pivotal member extending longitudinally of and bearing against the inner side of said stone, and spring means for holding said pivotal means in contact with the stone.

2. In a cylinder grinder, the combination with a rotatable block and a radially adjustable member therein, of a radially adjustable stone, a member extending longitudinally of the inner side of the stone and pivoted at one side thereof and having the other side free, and a plurality of springs bearing against the free side of said pivotal member to hold the stone extended uniformly from end to end.

3. In a cylinder grinder, the combination with a rotatable block having a plurality

of longitudinal radial slots and a common central passage connecting with said slots, holders slidably arranged in said slots having bevelled inner surfaces, adjustable tapered members engaging said bevelled surfaces and adapted to move said holders in uniform and equal adjustment, stones adjustably arranged in said holders, pivotal members within said holders bearing uniformly throughout the length of the inner side of the stones, and spring means for holding said pivotal members against said stones.

4. A cylinder grinder, comprising, a block

having a plurality of radial slots, stone holding members slidably arranged in said slots, said members being recessed longitudinally, plates extending longitudinally within the recesses of said holders and pivoted at one side thereof, a plurality of coil springs bedded in the bottom of the recesses and pressing outwardly against the free portion of the pivotal plate, stones slidably retained in said recesses and engaging said pivotal plates, and means for limiting the radial movement of said stones.

NELSON SARGENT.
